ATTORNEYS

UNITED STATES PATENT OFFICE.

ANDREW M. MCGILL, OF BETHLEHEM, PENNSYLVANIA.

CONSTRUCTION AND REPAIR OF RAILROAD CARS.

Application filed March 15, 1922. Serial No. 543,998.

To all whom it may concern:

Be it known that I, ANDREW M. MCGILL, a citizen of the United States, and a resident of Bethlehem, borough of Fountain 5 Hill, in the county of Lehigh and State of Pennsylvania, have made and invented certain new and useful Improvements in the Construction and Repair of Railroad Cars, of which the following is a specification.

10 My invention relates to the construction and repair of railroad cars, and particularly to refrigerator cars, milk cars, and other types of vertically sheathed wooden cars.

The underframing or sills of a wooden 15 car in time rot and decay, requiring that the sheathing be removed and the underframing be either repaired or replaced. The decaying and rotting of the sills and underframes and lower portion of the sheathing 20 take place particularly rapidly in refrigerator cars and milk cars, and the removal of the entire sheathing, repair of the underframing, and renewal of the sheathing involve an enormous amount of labor and expense annually to the railroads.

It is accordingly an object of my invention to provide a method whereby the underframing or sills of the car may be renewed without requiring the removal of the entire 30 sheathing, thus involving the saving of the majority of the car sheathing.

A further object is to provide a construction and method for the repair or renewal of the underframing or sills of a railroad 35 car which may be easily and readily carried out, involving but a small amount of labor and requiring the use of a minimum amount of raw material or sheathing.

A further object is to provide an improved 40 method for removing the lower portion only of the sheathing so as to expose the underframing or sills and thus provide for the easy and ready replacement or renewal of the underframing, after which the removed 45 portion of the sheathing may be replaced by new sheathing, and to provide in connection with such method a means for preventing water from entering between the joined sections of the sheathing.

50 A further object is to provide a car construction which may be applied to a car in the initial building, whereby the sheathing is divided into a main and upper portion and a supplemental lower portion, the latter 55 being readily removable so as to expose the

underframing and allow for its ready repair and renewal.

A further object is to accomplish the aforementioned ends in a simple and expeditious manner and to provide a particular 60 form of metal flashing which will prevent any entrance of moisture between the joints of the abutting ends of the sheathing and thus form a watertight and lasting construction.

65 With the foregoing and other objects in view, my invention consists in the improved method of construction and repair of railroad cars illustrated in the accompanying drawing and hereinafter described and 70 claimed, and in such variations and modifications thereof as will be obvious to those skilled in the art to which my invention relates, it being understood that changes may be made within the scope of what is claimed 75 without departing from the spirit of the invention.

In the accompanying drawings:

Figure 1 is a view in transverse section of a vertically sheathed wooden car and illustrating by dotted lines the manner in which the lower ends of the sheathing are cut or separated so as to be removed for the exposing and removing of the underframing or 80 side sills of the car;

85 Figure 2 is a view in perspective and partially in section of a car after having been repaired by my improved method or representing the construction of a new car which embodies the characteristic features of my 90 invention;

Figure 3 is a detail view in transverse section illustrating the juncture between the abutting extremities of the ends of the upper and unremoved portion of the sheathing 95 and the lower and replaced sheathing, the juncture being such that all moisture is prevented from entering therein; and

Figure 4 is a detail view in transverse section of a somewhat modified form of car 100 blocking strip which aids in holding the abutting ends of the sheathing in place and to which the sheathing is nailed.

Referring specifically to the several views, wherein similar reference numerals designate corresponding parts throughout, the side sill or underframing 10 of a vertically sheathed wooden car in time decays and rots, this action being particularly rapid when the car is used as a refrigerator or 110

milk car. In order to provide for the ready removal and replacement of the underframing or side sills 10 and to effectually carry this out without necessitating the entire removal of the sheathing S, as has heretofore been customary, I preferably attach to the lower portion 11 of the sheathing a straight edge or cleat 12 which serves as a guide platform for a motor driven circular saw 13 which is moved along the side of the car, preferably about twenty (20") inches above the lower extremity of the sheathing, and thus severs or cuts the vertical sheathing along the line 14, the saw being placed at an angle to the horizontal so that the slot 14 extends inwardly and upwardly and is located directly in front of one of the beams or stringers 15 which extend along the side walls of the car.

20 The sheathing is thus severed and divided into a main and upper section 16 and a smaller and lower section 11. The straight edge or cleat 12 is then removed and the lower section of the sheathing torn from the car body in any convenient manner so as to expose the decayed or rotted side sill or underframing 10. The decayed or rotted underframing is then removed and a new underframing or sill inserted in place. After 25 the repair of the underframing has been thus carried out, a metal flashing such as shown in detail in Figure 3 is inserted between the lower extremities of the upper portion of the sheathing 16 and the stringer 30 or beam 15.

This metal flashing is preferably composed of a flange 17, a downwardly and outwardly extending inclined body portion 18, and an exposed outer plate or flange 19. With the metal flashing thus in place, a new lower sheathing section 11 is cut along its upper edge at an angle or bevel so as to fit 40 snugly against the inclined body portion 18 of the flashing. The sheathing is then firmly nailed in place to the underframing in the customary manner, and the flashing is also secured in place by the nails or holding means 20. The lowermost edge of the sheathing 11 is then cut or trimmed by 45 means of the circular saw 13 which is moved downwardly to accomplish this particular purpose. In the majority of instances wherein the underframing or side sill of a car has decayed or rotted, it has been found 50 that the lower ends of the sheathing are also decayed or rotted, so that the replacement of the lower ends of the sheathing is necessary and is carried out without requiring the removal or replacement of the upper and main portion of the sheathing.

From the foregoing it will be readily appreciated that my improved method of car repair and car construction will result in a vast saving to the railroads, especially when 55 the vast number of cars of this particular

type which are in use are considered. Those cars which are used for the transportation of liquid, such as milk or refrigerator cars, are particularly liable to rot and decay in a comparatively short time, so that their frequent repair is necessary. With my improved method, the larger and undecayed portion of the sheathing is thus saved, and, further, the entire repair can be carried out with a minimum amount of labor and 75 trouble.

My improved car construction can be followed out in the initial building of the car as illustrated in Figure 2. The car shown in Figure 2 is what is known as a milk car and comprises the usual side sill or underframing 21 and is provided with a blocking or nailing strip 22. The sheathing S is divided into a permanent and upper main section 23 and a smaller and lower removable section 24, the two sections abutting and being secured together at the metal flashing 25 which extends longitudinally of the car sides. With the car as thus initially constructed, the underframing may be readily exposed for repair or renewal by removing the lower section of the sheathing and after the repairs have been carried out a new lower section of sheathing may be 85 economically inserted in place.

In some instances I have found it desirable to provide a somewhat modified form of blocking or stringer, sometimes termed a nailing strip, such as illustrated in Figure 4, the strip in question being provided with an outwardly projecting portion having the upper inclined ledge 28 and lower routed out portion 29, thus providing for the reception and securement of the ends 30 and 31 of the upper and lower sections of the sheathing, respectively, and for the proper nesting of the metal flashing thereagainst. The downwardly extending body of the metal flashing, together with the flange 17, effectually prevents any water from seeping in between the abutting ends of the sheathing and thus provides for the 90 long and serviceable life of the car.

Having thus described and explained my invention, I claim and desire to secure by 95 Letters Patent:

1. The method of car repair consisting in cutting the sheathing longitudinally of the car on an angle extending downwardly and outwardly, removing the lower so-formed 100 section of the sheathing for the exposing of the sill, repairing or renewing the sill, replacing or renewing the removed sheathing, the upper ends of the replaced sheathing being cut at an angle similar to the aforementioned cut in the sheathing.

2. The method of car repair consisting in cutting the sheathing longitudinally of the car on an angle extending downwardly and outwardly, removing the lower so-formed 105

- section of the sheathing for the exposing of the sill, repairing or renewing the sill, replacing or renewing the removed sheathing, the upper ends of the replaced sheathing being cut at an angle similar to the aforementioned cut in the sheathing, and placing a metal flashing between the abutting extremities of the sheathing sections for the protection thereof.
- 10 3. The method of repair of vertically sheathed wooden cars consisting in placing a straight edge or cleat longitudinally along the car body a slight distance above the lower ends of the sheathing, moving a cutting saw along said car body guided by said straight edge or cleat, and severing the sheathing so as to divide the same into an upper and main section and a lower supplemental section, removing the so-formed lower supplemental section of the sheathing and exposing the underframing or sills of the car, repairing or renewing the underframing or sills, and replacing or renewing the lower section of the sheathing.
- 15 4. The method of repair of vertically sheathed wooden cars consisting in placing a straight edge or cleat longitudinally along the car body a slight distance above the lower ends of the sheathing, moving a cutting saw along said car body guided by said straight edge or cleat, severing the sheathing so as to divide the same into an upper and main section and a lower supplemental section, removing the so-formed lower supplemental section of the sheathing and exposing the underframing or sills of the car, repairing or renewing the underframing or sills, replacing or renewing the lower section of the sheathing, and placing a metal flashing
- 20 between the abutting extremities of the upper and lower sections of the sheathing.
- 40 5. The method of repair of vertically sheathed railroad cars consisting in placing a straight edge or cleat longitudinally along the body of the car and spaced a slight distance above the lower extremity of the sheathing, moving a cutting saw along said car body guided by said cleats, and severing the sheathing at an angle extending upwardly and inwardly and thus dividing the sheathing into an upper main section and a lower supplemental section, removing the lower supplemental section and exposing the underframing or sills of the car, repairing or renewing the underframing or sills, placing a metal flashing adjacent the lower extremity of the upper section of the sheathing and replacing or renewing the lower sheathing section and placing the upper extremity thereof in contact with said metal flashing for the protection of the abutting extremities of the sheathing sections.
- 25 6. A car construction comprising sheathing formed in upper and lower sections, the abutting extremities thereof being cut or formed along an angle extending downwardly and outwardly from the car, and a metal flashing extending between the abutting ends of the upper and lower sections of the sheathing.
- 30 Signed at Bethlehem, borough of Fountain Hill, in the county of Lehigh and State of Penna., this 23rd day of January, A. D. 1922.
